US0D1051209S

(12) **United States Design Patent** (10) Patent No.: **US D1,051,209 S**
(45) Date of Patent: ** Nov. 12, 2024

(54) **DRONE FILTER**

(71) Applicant: **Shenzhen Wurenji Technology Co., Ltd.**, Shenzhen (CN)

(72) Inventor: **Yingqing Ji**, Heyuan (CN)

(**) Term: **15 Years**

(21) Appl. No.: **29/914,456**

(22) Filed: **Oct. 18, 2023**

(51) LOC (14) Cl. **16-05**

(52) U.S. Cl.

USPC **D16/237**; D16/219

(58) **Field of Classification Search**

USPC D21/430, 436-455, 390, 398; D12/1-4, D12/16.1, 319-345; D16/130, 200, 207, D16/210-213, 217-220, 237; D23/365

CPC G02B 5/208; G02B 1/041; G02B 5/20; G02B 5/22; G02B 5/282; G03B 11/00; G03B 7/18

(57) **CLAIM**

The ornamental design for a drone filter, as shown and described.

DESCRIPTION

FIG. 1 is a front perspective view of a drone filter, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.
